BARNET M. JOHNSON

By Earl M. Sinclair Atty.

UNITED STATES PATENT OFFICE.

BARNET M. JOHNSON, OF BURLINGTON, COLORADO.

METALLIC RAILWAY-TIE AND FASTENING.

1,162,067.

Specification of Letters Patent. Patented Nov. 30, 1915.

Application filed March 15, 1915. Serial No. 14,500.

To all whom it may concern:

Be it known that I, BARNET M. JOHNSON, a citizen of the United States of America, and resident of Burlington, Kit Carson county, Colorado, have invented a new and useful Metallic Railway-Tie and Fastening, of which the following is a specification.

The object of this invention is to provide an improved construction for a metallic rail-
10 way tie.

A further object of this invention is to provide improved means for mounting a railway rail relative to a tie.

A further object of this invention is to provide improved securing or fastening means for a rail.

My invention consists in the construction, arrangement and combination of elements hereinafter set forth, pointed out in my
20 claims and illustrated by the accompanying drawing, in which—

Figure 1 is a sectional elevation showing a part of my improved tie and rail securing means, the cover plates being removed. Fig.
25 2 is a view similar to Fig. 1 showing the cover plates in place. Fig. 3 is a plan view, one of the cover plates being removed. Fig. 4 is a cross-section on the line 4—4 of Fig. 2. Fig. 5 is a detail of certain of the rail
30 securing means.

In the construction of the devices as shown the numeral 10 designates a railway tie which is formed of metal, is rectangular in cross-section, is hollow, and may be left
35 open at both ends. The tie 10 is formed, adjacent each end, with an upwardly opening recess, 11, extending from side to side of the tie and approximately half way from top to bottom thereof. A plate 12 is loosely
40 mounted in each recess 11 and is yieldingly supported therein by relatively heavy coil springs 13, in this instance four in number for each plate. The springs 13 are held in place by downwardly projecting lugs 14 on
45 the bottom of the plates 12, and by upwardly projecting lugs 15 fixed to the inside of the bottom of the tie, and engaging within the upper and lower ends, respectively, of said springs.

50 Upward movement of the plates 12 is limited by inwardly projecting stop lugs 16 formed on and projecting from the upper side margins of the recesses 11.

Railway rails, such as 17, are mounted
55 across the ties 10 within the recesses 11 and supported on the plates 12.

Accidental displacement of the plates 12 from the recesses 11, by endwise movement, is prevented by plates 18 secured to the side margins of said recesses.

The rails 17 are fastened to the plates 12 by means of headed bolts 19 having their heads, which are abnormally elongated in one direction, engaging the bases of the rails. The bolts 19 pass through apertures 65 in the plates 12 and are threaded on their lower ends and secured by nuts 20.

Partitions 21, 22 preferably are mounted within the ties 10 at opposite ends of the recesses 11, to prevent the entrance of snow and dirt to the part of the tie containing the springs 13. The partitions 22 which are at the end of the recess adjacent the inner side of the rail 17, need not extend entirely to the bottom of the tie, as indicated by dotted 70 lines in Fig. 1. Cover plates 23, 24 are mounted on opposite sides of the rails 17, over the recesses 11, and extend downwardly over the sides of the tie, and cover the top and sides of the recesses 11, except where 75 they are cut away, as shown in Fig. 2, to permit downward movement of the rails.

The tie 10 preferably is formed with transverse ribs 25 on its bottom to prevent slipping of the tie.

I claim as my invention—

1. A device of the class described, comprising a hollow tie open at its ends and formed with transverse recesses adjacent its ends and extending down its side walls, 90 partitions within said tie at opposite sides of each recess, plates yieldingly supported in said recesses, and rails mounted on and secured to said plates.

2. A device of the class described, comprising a hollow tie formed of metal, open at its ends and having recesses adjacent its ends, partitions within said tie at opposite sides of each recess, the inner partitions being spaced from the bottom of the tie, coil 95 springs mounted in said tie and projecting upwardly within said recesses, plates mounted on said springs, rails secured to said plates, and means to limit upward movement 100 of said plates.

3. A device of the class described, comprising a hollow tie formed of metal and having an upwardly opening recess adjacent each end, rail-bearing plates yieldingly mounted in said recesses, and plates removably secured to said tie at the ends of and overlapping said recesses and preventing 110

longitudinal movement of said rail-bearing plates.

4. A device of the class described, comprising a hollow metallic tie having an upwardly opening recess adjacent each end, a plate yieldingly supported in each recess and adapted to carry a railway rail, and a cover plate mounted on each side of each rail and covering said recesses.
- 10 5. A device of the class described, comprising a hollow metallic tie having an upwardly opening recess adjacent each end, a

plate yieldingly supported in each recess and adapted to carry a railway rail, a cover plate mounted on each side of each rail and covering said recesses, and partitions within said tie at each side of each recess.

15 Signed by me at Burlington, Colorado, this eighteenth day of February, 1915.

BARNET M. JOHNSON.
